(57) **CLAIM**

The ornamental design for a bicycle cuff lock, as shown and described.

DESCRIPTION

FIG. 1 is a perspective view of a bicycle cuff lock showing the new design;

FIG. 2 is a right view of the bicycle cuff lock of FIG. 1;

FIG. 3 is a front end view of the bicycle cuff lock of FIG. 1;

FIG. 4 is a bottom view of the bicycle cuff lock of FIG. 1; FIG. 5 is back end view of the bicycle cuff lock of FIG. 1; FIG. 6 is a left view of the bicycle cuff lock of FIG. 1; FIG. 7 is a top of the bicycle cuff lock shown in FIG. 1; FIG. 8 is a perspective view of a bicycle cuff lock shown in FIG. 1 showing the cuff locks engaged;

FIG. 9 is a right view of the bicycle cuff lock of FIG. 8; FIG. 10 is a front end view of the bicycle cuff lock of FIG. 8;

FIG. 11 is a bottom view of the bicycle cuff lock of FIG. 8; FIG. 12 is back end view of the bicycle cuff lock of FIG. 8; FIG. 13 is a left view of the bicycle cuff lock of FIG. 8; FIG. 14 is a top of the bicycle cuff lock shown in FIG. 8; FIG. 15 is a perspective view of a second embodiment of a bicycle cuff lock showing the new design;

FIG. 16 is a right view of the bicycle cuff lock of FIG. 15; FIG. 17 is a front end view of the bicycle cuff lock of FIG. 15;

FIG. 18 is a bottom view of the bicycle cuff lock of FIG. 15; FIG. 19 is back end view of the bicycle cuff lock of FIG. 15; FIG. 20 is a left view of the bicycle cuff lock of FIG. 15; FIG. 21 is a top of the bicycle cuff lock shown in FIG. 15; FIG. 22 is a perspective view of a bicycle cuff lock shown in FIG. 15 showing the cuff locks engaged;

FIG. 23 is a right view of the bicycle cuff lock of FIG. 22; FIG. 24 is a front end view of the bicycle cuff lock of FIG. 22;

FIG. 25 is a bottom view of the bicycle cuff lock of FIG. 22; FIG. 26 is back end view of the bicycle cuff of FIG. 22; FIG. 27 is a left view of the bicycle cuff lock of FIG. 22; FIG. 28 is a top of the bicycle cuff lock shown in FIG. 22; FIG. 29 is a perspective view of a third embodiment of a bicycle cuff lock showing the new design;

FIG. 30 is a right view of the bicycle cuff lock of FIG. 29; FIG. 31 is a front end view of the bicycle cuff lock of FIG. 29;

FIG. 32 is a bottom view of the bicycle cuff lock of FIG. 29; FIG. 33 is back end view of the bicycle cuff lock of FIG. 29; and,

FIG. 34 is a left view of the bicycle cuff lock of FIG. 29.
